UNITED STATES PATENT OFFICE.

CHRISTIAN ANDERSON, OF MINNEAPOLIS, MINNESOTA.

DESIGN FOR A BOTTLE.

Application filed April 15, 1926. Serial No. 17,307. Term of patent 14 years.

To all whom it may concern:

Be it known that I, CHRISTIAN ANDERSON, a citizen of the United States, residing at 237 Fourteenth Ave. South, city of Minneapolis, in the county of Hennepin and State of Minnesota, have invented a new, original, and ornamental Design for Bottles, of which the following is a specification, reference being had to the accompanying drawing, forming part thereof.

The figure is a side view in elevation of a bottle, showing my new design.

I claim:

The ornamental design for a bottle, as shown.

CHRIS. ANDERSON.
